(57) **CLAIM**

The ornamental design for a foot control, as shown and described.

DESCRIPTION

The present application is related to U.S. Ser. No. 29/199,011, entitled Foot Control and U.S. Ser. No. 10/814,974, entitled Foot Control, filed on even date herewith.

FIG. 1 is a front perspective view of a foot control incorporating the design of our invention;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The features of the foot control shown in phantom lines are not elements of the design of our invention.
